CONDENSING APPARATUS FOR CARDING MACHINES.

1,103,541.

Specification of Letters Patent.

Patented July 14, 1914.

Application filed November 20, 1912. Serial No. 732,456.

To all whom it may concern:

Be it known that I, WILLIAM D. RUNDLETT, a citizen of the United States, and resident of North Andover, county of Essex,

5 State of Massachusetts, have invented an Improvement in Condensing Apparatus for Carding Machines, of which the following description, in connection with the accompanying drawing, is a specification, like 10 characters on the drawing representing like parts.

This invention relates particularly to condensing apparatus for carding machines used for treating jute waste and similar 15 refractory and short-fibered material to facilitate the manufacture of yarn therefrom.

Jute, jute waste, gunny bagging, and the like, is exceedingly difficult to treat in a rapid and economical manner between the 20 carding and spinning operations, for while such material can be carded readily the resulting thin film or sheet of sliver taken from the doffing point has so little inherent strength and coherence that it is exceedingly 25 difficult to condense or compact the same efficiently in order that the condensed sliver may be manipulated and treated readily in subsequent operations.

My present invention has for its object 30 to provide a novel and simple condensing apparatus for carding machines so constructed and arranged that refractory and short-fibered material such as hereinbefore referred to can be treated in a rapid, 35 economical and satisfactory manner.

In accordance with my invention the film or sheet of sliver is conveyed in a direct, flat and downwardly inclined path extending tangentially from the doffing point to the 40 condensing device without any change or deviation until the film or sheet is very close to the trumpet forming a part of the condensing device, thereby reducing to a minimum the tendency of the sliver to rupture 45 or break and increasing the output.

In treating such a material as jute waste the maximum production of the machine is desired, insuring the delivery from the doffer of a film or sheet of sliver of reasonable 50 thickness, but it could not support itself through the necessary distance between the doffing point and the point at which condensation of the sliver is effected. This

distance must be long enough to permit convenient and ready piecing-up of the sliver 55 when it breaks, and such distance must be traversed by the sliver.

In my present invention I sustain the sliver practically the entire distance between the doffing and condensing points, and for 60 such purpose I interpose therebetween a smooth, flat and preferably polished support placed at such an angle that while the sliver is sustained the various forces acting upon the same will operate conjointly to 65 cause a uniform and uninterrupted flow thereof over the support to the condensing point.

The push of the vibrating comb which crowds the sliver away from the doffing point imparts the desired body or thickness 70 to the film and also tends to keep it moving downward over the support, the slight frictional resistance of the latter being overcome by the vibration of the machine and 75 the angle of inclination of the support, the supported film or sheet of sliver being assisted to travel with sufficient rapidity by the action of gravity and the draft of the rolls of the condensing apparatus. Manifestly the rate of travel of the sliver must be 80 practically uniform and at such speed that the film or sheet will not be ruptured before it reaches the condensing means nor unduly compacted or choked into the trumpet. 85

Herein the condensing means comprises a trumpet which is disposed centrally with relation to the approaching film or sheet of sliver, and condensing rolls which receive between them and condense the gathered in 90 sliver as it emerges from the trumpet. Said trumpet gathers in the film or sheet from a point very near its mouth and the delivery nose of the trumpet is located as close as possible to the nip of the condensing rolls. 95 The gathering together of the sheet of sliver at the mouth of the trumpet is caused mainly and primarily by the draft of the condensing rolls located adjacent the delivery end of the trumpet.

Sliver breakage may be due to rupture of the film before it reaches the trumpet, or the rupture may occur at the rolls by reason of the material choking in the trumpet, hence the various forces acting upon the 105 sliver after it leaves the doffing point must

be properly balanced relatively to each other in order to insure a maximum product.

The carded material is doffed in a plurality of distinct and separate and relatively narrow sheets or films in any suitable or usual manner, as by ring-doffers, by special arrangement of the card-clothing on the main cylinder, or otherwise, and forming no part of my present invention, the same being well known in the art.

Each sheet or film of sliver travels from the doffing point direct to its own particular condensing means, and I have provided the inclined sliver support, which preferably extends across the machine, with upright and parallel partitions which maintain separated adjacent slivers.

The arrangement of the partitions parallel to the flow or travel of the slivers over the support obviates any tendency to hold back or retard the edges of a sliver, with consequent rupture, and when any particular sliver breaks it can be pieced-up readily and quickly without interfering with the adjacent slivers.

In actual practice the gathering in or contraction of the film or sheet of sliver is very sudden, that is, it begins very close to the mouth of the trumpet, so that the angle between the trumpet and the sides of the sliver of full width is very obtuse, as will be shown hereinafter, said gathering in, as above stated, being due mainly to the draft of the condensing rolls.

To prevent the collection of small particles of fiber in the corners formed by the separating partitions and the plate in which the trumpet is set I prefer to curve the lower ends of each pair of partitions inward toward the mouth of the trumpet, the curvature corresponding substantially to the contour of the sliver adjacent thereto. Such curved portions prevent accumulations of fiber and obviate the breakage of sliver which would occur inevitably should the sliver edges contact with such an accumulation.

The various novel features of my invention will be fully described in the subjoined specification and particularly pointed out in the following claims.

Figure 1 is a side elevation and part section of a sufficient portion of a carding machine to be understood, with one practical form of my present invention embodied therein, the section being taken on the line 1—1 Fig. 2; Fig. 2 is a left hand end view of a portion of the mechanism shown in Fig. 1, showing the rolls of two of the condensing devices, and a portion of the transversely extended sliver support; Fig. 3 is a plan view, on a smaller scale, of a portion of the sliver support, to show more clearly the gathering in of the film or sheet of sliver by the trumpet of the con-

densing apparatus, the trumpet being shown in section.

Referring to the drawing, Fig. 1, I have shown at 1 a portion of a doffing roll or cylinder, suitably clothed at 2 to take the carded material from the main cylinder, (not shown) the material being doffed in a plurality of distinct sheets or films of sliver, said roll 1 turning in the direction of the arrow 3 and having an attached gear 4.

The frame sides 5 are provided with stands, as 6, having suitable bearings for the comb shaft 7 provided with arms 8 carrying the vibrating comb 9, the latter being vibrated in any suitable or usual manner to comb from the doffing roll 1 the sheets or films of sliver. At the end of the main frame the stands 6 are extended at 10 and connected by a rigid cross-brace 11 upon which the condensing apparatus is mounted at some distance away from and below the comb, such apparatus comprehending a plurality of units each of which consists essentially of a trumpet or sliver gatherer 12, Figs. 1 and 3, and an adjacent co-operating pair of condensing rolls 13, 14, parallel to the axis of rotation of the doffing cylinder.

Each pair of rolls is shown as mounted in a suitable frame comprising a base 15 and upturned sides 16, having suitable bearings for the rolls, the latter having attached intermeshing gears 17, 18, respectively, driven by gears 19, Fig. 2, on a transverse shaft 20 having its bearings in the stands 6. This shaft is driven in any suitable manner, herein shown as by gears 21, 22 from the large gear 4. It will be seen that the sides 16 of the roll frames are inclined, and upon the upright edges thereof toward the doffer cylinder 1 is secured a transverse plate 23 having apertures therein in which are set the trumpets 12, the plate being at right angles to the plane of travel of the slivers between the doffing and condensing points, the axes of the trumpets being parallel to such plane of travel and slightly above the same, as shown in Fig. 1.

While I have herein shown the trumpets arranged with their axes parallel to the plane of travel of the sliver it is to be understood that the invention is not to be limited to the specific form shown and described, as various modifications thereof may be made without departing from the spirit and scope of the invention as set forth in the appended claims.

The doffing point is the point at which the comb takes the sliver from the doffing cylinder, and extending tangentially from this point to the trumpet plate 23 I interpose a sliver support 24, preferably a flat plate of metal having its upper surface polished to minimize friction and extended transversely of the frame.

A cross-girth, 25 is fixedly secured at its

ends by bolts 26 to the stands 6 and upon said cross-girth the supporting plate 24 is rigidly mounted, the angle of such sliver support or plate being such that while the 5 sliver is effectually supported it will travel or flow freely along the surface of the support as the action of gravity, the push of the comb upon the sliver, the draft of the condensing rolls, and the vibration of the machine 10 operate conjointly upon the sliver.

In order to bring the plane of the support as near as is desirable to the axis of the trumpet the latter is cut away at its lower edge, as at 27, Fig. 1. The distance between 15 the doffing point and the mouth of the trumpet is amply sufficient to permit the necessary manipulation when piecing-up the sliver, as will be apparent from Fig. 1.

A series of upright and parallel partitions 20 or guides 28 are mounted on the support 24, separated from each other a greater distance than the width of a sheet or film of sliver 29, Fig. 3, which traverses the support between each pair of guides, the latter being 25 also parallel to the direction of travel of the slivers. These guides separate adjacent slivers, so that if any one of them breaks or spreads unduly as it passes over the inclined support it will not interfere with an adjacent 30 sliver.

I have found in practice that a sliver say about $7\frac{1}{2}$ inches wide will be readily gathered in by a trumpet having a diameter at its mouth of about $1\frac{1}{2}$ inches, and an internal 35 nose diameter of say $\frac{3}{16}$ of an inch, but it will be understood that these dimensions are variable, and are employed for illustrative purposes and not in any limiting sense.

The sheet or film of sliver flows downward over the inclined support 24 and at a 40 point quite close to the mouth of the trumpet the latter gathers in and somewhat compacts the sliver, sufficiently for the compacted mass to travel the short distance from 45 the support to the lower portion of the trumpet without breakage. The compacted, rope-like sliver is delivered by the nose of the trumpet to the condensing rolls 13, 14, as close as possible to the nip thereof, and 50 the compressing and condensing action exerted by the rolls so strengthens the sliver that it can be treated readily in subsequent operations, the condensed sliver or slubbing, indicated at 30, Fig. 1, passing over the 55 cross-plate 11 and an apron 31 to suitable cans, not shown. It will be seen that the sliver is supported the entire distance from the doffing point to the trumpet with the exception of the very short space immediately 60 adjacent the trumpet lip, over which short space the sliver, then gathered together and partly compacted, will readily support itself.

The spread out sheet or film of sliver if 65 unsupported, cannot span the requisite dis-

tance between the doffing point and the condensing means, and this is particularly so nearer the doffing point, where the agitation of the sliver is greatest. If the support be horizontal, or nearly so, the forces acting 70 upon the sliver cannot effect the travel thereof to the condensing means, as the inertia of the sliver and the frictional resistance are too great to be overcome by the very slight coherence of the fibers forming the sliver. 75 Consequently the support must be inclined at such an angle that frictional resistance to travel of the sliver is so diminished as to enable the draft of the rolls to exert itself upon the sliver, while the thickness of the 80 latter is regulated by the accumulation due to the doffing comb relatively to the speed of travel of the sliver, and an even, smooth and uniform flow of the sliver over the support is attained. Obviously the inclination of 85 the sliver support determines the height of the trumpet relatively to the doffing point. It may be stated that the thinner the sheet or film of sliver and the shorter the fibers composing the same the greater the inclination 90 of the sliver support 24. Theoretically, if the trumpet were placed very near the doffing point, so that the gathering-in action of the trumpet upon the sliver would begin almost as soon as the sliver leaves the comb, 95 it is possible that under such conditions the sliver would draw directly into the trumpet without an intermediate support. The conditions of practical operation, as to piecing-up or starting a sliver, absolutely preclude 100 such an arrangement of the mechanism even should the material or stock lend itself thereto.

Referring to Fig. 3, wherein I have indicated at 32 the gathering in of the sheet or 105 film of sliver 29, it will be seen that the narrowing or gathering in begins at a very short distance from the mouth of the trumpet 12, making a very blunt or obtuse angle, and dead spaces are left adjacent the trumpet 110 plate 23 and at each side of the gathered in sliver. To prevent small particles of fiber, fluff, or fly from lodging therein and collecting to interfere with the travel of the sliver I provide inturned curved extensions 33 at 115 the lower ends of each pair of guides or partitions 28, said extensions being curved substantially to conform to the contour of the gathered in edges of the sliver. Such extensions prevent the collection of small particles in the dead spaces and do not interfere in the least with the travel of the sliver, 120 nor in fact do they act as guides therefor.

By the construction herein shown the sliver travels in a straight path directly 125 from the doffing point to the condensing means, conforming to the placing of the combed fibers in the sliver, so that there is practically no alteration in the path of movement of the fibers nor any abrupt re- 130

positioning of the same throughout the operation, thereby facilitating the maximum production of the machine and greatly improving the strength and uniformity of the 5 condensed sliver, and enabling it to be twisted and spun with greater ease in subsequent operations.

My invention is not restricted to the precise construction and arrangement herein 10 shown and described, for the same may be modified or re-arranged in various details by those skilled in the art without departing from the spirit and scope of my invention as set forth in the claims hereunto annexed.

15 Having fully described my invention, what I claim as new and desire to secure by Letters Patent is:

1. The combination, in a carding machine having means to doff and deliver a sheet of 20 sliver, of sliver condensing means comprising a trumpet and positively driven rolls, located below and at a distance from the doffing point to enable the sliver to maintain a flat ribbon form for a considerable extent to permit ready piecing up and starting 25 of the sliver, and means extending substantially tangentially from the doffing point to support the sliver in a straight, direct and inclined path of movement between the said doffing point and the trumpet while per-

mitting a uniform and uninterrupted flow of the sliver upon said support.

2. The combination, in a carding machine adapted to doff and deliver side by side a plurality of sheets of sliver, of a trumpet 35 and coöperating condensing rolls for each sliver, located below and at a distance from the doffing point to enable each sheet of sliver to maintain its flat ribbon form for a considerable extent to permit ready piecing 40 up, an inclined, flat support arranged with its upper end substantially tangential to the doffing point to sustain the several sheets of sliver in direct and parallel paths of movement between the said doffing point and the 45 several trumpets while permitting unimpeded flow of the sheets of sliver over the support, and upright partitions on the support between and to maintain separated adjacent sheets of sliver, said partitions being 50 parallel to each other and to the direction of travel of the sheets of sliver.

In testimony whereof, I have signed my name to this specification, in the presence of two subscribing witnesses.

WILLIAM D. RUNDLETT.
